STRIPER

Samuel B. Beugler, Los Angeles, Calif.

Application September 12, 1933, Serial No. 689,072

3 Claims. (Cl. 91—62.6)

This invention has to do in a general way with the art of painting and is more particularly related to mechanical stripers, such as are used in painting lines or stripes on automobiles, furniture, and the like, for decorative purposes. The general construction of a stiper of this nature comprises: a barrel or tube adapted to contain the paint, such barrel having an end closure which is slotted for the reception of a 10 rotatable wheel plate. In the operation of this device the paint or lacquer is placed in the barrel and the wheel is rotated in engagement with the surface to be striped, the paint being carried by capillary or viscosity action along the 15 periphery of the wheel which applies it to the surface.

All devices of this character, with which I am familiar, have an inherent defect in that 20 part of the paint or lacquer is carried by the wheel beyond the point of application, running down the face of the wheel as it traverses its upper course and being wiped off the wheel by the top portion of the slot so that it drips onto the surface being striped.

Various attempts have been made to eradicate 25 this defect, such as mounting a packing or filter unit in the end of the barrel against which the wheel wipes, the object of such construction being to limit the amount of paint delivered to the wheel. In another device, a compound system of wheels is employed. None of 30 these devices has proved satisfactory.

It, therefore, becomes a primary object of this 35 invention to produce a striping device of the class described in which the defect, above referred to, is entirely eliminated. This object I accomplish by forming the slot through which the wheel rotates in a manner such that all of the paint adhering to the wheel, after it has 40 engaged the surface being striped, is carried back into the barrel. More specifically, therefore, my invention contemplates a novel type of slot formation whereby this objective can be obtained.

Since it is desirable in a striping device of 45 this character to have a device which can be employed in forming strips of different widths, I propose to construct the device contemplated by this invention with a removable closure cap 50 which carries the striping wheel whereby a plurality of such caps having wheels of different widths can be employed with the same barrel. In this connection, it is still another object of 55 this invention to provide a device of the class described with novel means for locking or holding the cap in place.

The details in the construction of a preferred 60 form of my invention, together with other objects attending its production, will be best understood from the following description of the

accompanying drawing which is chosen for illustrative purposes only and in which—

Fig. 1 is a side elevation with parts broken away showing a preferred form of the invention;

Fig. 2 is an enlarged partial section further illustrating the construction of the cap or spring head contemplated by this invention; 5

Fig. 3 is a sectional elevation taken on the line 3—3 of Fig. 2;

Fig. 4 is an end elevation taken in the direction of the arrow 4 in Fig. 2; and 10

Fig. 5 is a plan section taken on the line 5—5 of Fig. 4.

More particularly describing the invention, as herein illustrated, reference numeral 11 indicates a barrel or tube which has a closure 12 on one end through which a plunger rod 13 slidably extends. The plunger rod 13 is provided with a plunger 14 within the barrel and has a button 15 on its outer end. Reference 15 numeral 16 indicates an embossed portion formed on the top of the barrel, such portion being provided with a pair of oppositely disposed slots 17 and 17', which are enlarged at their inner ends for the reception of guide bars 20 18 and 18'. The guide bars are locked in the slots by means of thumb screws 19 and 19'. It will be understood that various types of guide bars may be employed, depending upon the work 25 in connection with which the device is used, the use of such guide bars being well known to those 30 familiar with the art.

Reference numeral 20 indicates a cap or head 35 which is shown as comprising a collar 21 fitted over the open end of the barrel 14 and an end closure 22. The end closure plate 22 is preferably made of appreciable thickness or, as shown, is provided with a forwardly extending lug or boss 23 which has a downwardly extending projection 24. This projection 24 provides a convenient means for guiding the stiper with an ordinary "straight edge" or ruler, and is an important and novel feature of the device contemplated by my invention. The cap or head 20 is provided in its bottom portion with a slot, such 40 slot having a portion 25 extending into the collar flange 21 and another portion 26 in the end closure, or, more specifically, in the bottom portion of the boss 23. The slot, which is formed by the slot portions 25 and 26, just referred to, 45 communicates with the interior of the barrel and contains a striping wheel plate 27 which is rotatably mounted in this slot upon a pin 28 which in turn is mounted in the lower bifurcated end portion 24 of the boss 23. This wheel 50 plate may be of any desired width, depending upon the width of strip desired and its periphery may be knurled as is well known to those 55 familiar with the art. The radius of the wheel, however, must be such that it has a segment 60

extending through the two slot portions 25 and 26 into the interior of the barrel.

For the purpose of admitting the segment of the wheel extending into the barrel, as just 5 pointed out, I provide the end of the barrel with a notch indicated at 30. In order that the paint withdrawn from the barrel by the wheel during its rotation may be confined, as far as possible, to the edge of the wheel, I form the slot portion 25 in the collar flange 21 so that its sides are in substantial sliding engagement with the 10 face of the wheel. The depth of this slot, however, is such that its inner end 31 is spaced a slight distance away from the periphery of the wheel. These two features are best illustrated 15 in Figs. 2, 3, and 5.

It was pointed out above as the primary object of this invention to form a head construction of the class described so that all of the paint adhering to the wheel after it has engaged the surface being striped is carried by the wheel back into the barrel instead of being wiped off by the edges of the slot whereby the dripping of paint onto the work, which occurs in the conventional stiper, is eliminated. This is accomplished by forming the upper part of the slot portion 26 through which the wheel rotates in passing into the barrel of a width and shape such that a substantial space surrounds both 25 the edge and the side surfaces of the wheel when it is rotating into the barrel. I have found that for most satisfactory operation it is important that the slot portion 26 be made substantially larger at its outer edge 32 than it is at its inner edge 33 where the wheel rotates into the barrel. In other words, it is important that the wall of 30 the slot diverge outwardly away from the inner edge or inner end 33 thereof. It is also important, as pointed out above, that the portion 35 of the slot which is adjacent the lower half of the wheel, or adjacent that portion of the wheel which is rotating away from the barrel, be in substantial sliding engagement with the side faces of 40 the wheel, and it is therefore necessary that, in addition to diverging outwardly from the inner 45 end 33, the slot portion 26 must also converge downwardly toward the axis of the wheel. The first feature mentioned above is best illustrated in Figs. 2 and 5, and the last mentioned feature 50 is best illustrated in Fig. 4.

In addition to the slot construction just described, it has been previously pointed out that my invention also contemplates means for frictionally holding the cap or head member on the 55 barrel. This last mentioned means constitutes a spring finger 35 which is formed on the end of the barrel by a short helical kerf 36.

In the operation of this device, the plunger 14 is withdrawn to the desired point in the barrel, the cap or head 20 is removed, and the desired quantity of paint or lacquer is poured into the barrel. A striping head having a wheel of the desired width is then placed over the open end of the barrel; the plunger is pressed forward 60 to bring the paint into slight pressure contact with the interior of the striping head. Guides of the desired type are then set to the position required and the device is drawn along the object to be striped so as to rotate the "inside" segment of the striping wheel downwardly out of 70

the barrel. In this manner the paint is carried by capillary or viscosity action along the edge of the wheel and is applied to the surface being striped. Any paint which adheres to the wheel after it traverses the surface is carried back into the barrel, since there is no way in which it can be wiped off or drip onto and spoil the work. The plunger may be compressed from time to time by the application of pressure on the button 15 in a manner well known to those familiar with the art. 10

It is to be understood that, while I have herein described and illustrated one preferred form of my invention, the invention is not limited to the precise construction described above but includes within its scope whatever changes fairly come within the spirit of the appended claims. 15

I claim as my invention:

1. A paint stiper of the class described embodying: a barrel; a head on the end of said barrel having a face plate and provided with a slot which communicates with the interior of said barrel; and a striping wheel rotatably mounted in said slot with a segment of its periphery in said barrel, said slot and said wheel being arranged so that the periphery of said wheel enters said barrel through said face plate and leaves said barrel through its wall and a portion of said slot above the central portion of said wheel being enlarged to provide a substantial space around the upper segment of said wheel which enters said barrel during its rotation whereby paint adhering to said wheel is carried back into said barrel. 25

2. A paint stiper of the class described embodying: a barrel; a head on the end of said barrel having a face plate and provided with a slot which communicates with the interior of said barrel; and a striping wheel rotatably mounted in said slot with a segment of its periphery in said barrel, said slot and said wheel being arranged so that the periphery of said wheel enters said barrel through said face plate and leaves said barrel through its wall and a portion of said slot above the central portion of said wheel being enlarged and tapered to provide an inwardly tapered space around the upper segment of said wheel entering said barrel during its rotation whereby paint adhering to said wheel is carried back into said barrel. 45

3. A paint stiper of the class described embodying: a barrel; a head comprising an end closure and a collar flange mounted on the end of said barrel, said head member having a corner slot extending through a portion of said end closure and said collar flange into said barrel; and a striping wheel plate rotatably mounted in said slot with a segment of its periphery projecting into said barrel, the portion of said slot in said side flange being formed with its sides in substantial engagement with the faces of said wheel plate and its end spaced away from the periphery of said wheel plate, and the portion of said slot in said end closure being spaced away from both the sides and periphery of said wheel, the wall of said last mentioned slot portion being formed so as to diverge outwardly away from its inner edge. 55 60 65
